UNITED STATES PATENT OFFICE.

WALTER FERRIS, OF SOUTH MILWAUKEE, WISCONSIN, ASSIGNOR TO THE
BUCYRUS COMPANY, OF SOUTH MILWAUKEE, WISCONSIN, A CORPORA-
TION OF WISCONSIN.

MACHINE-BRAKE.

No. 853,348.

Specification of Letters Patent.

Patented May 14, 1907.

Application filed July 11, 1906. Serial No. 325,605.

To all whom it may concern:

Be it known that I, WALTER FERRIS, a citizen of the United States, residing at South Milwaukee, county of Milwaukee, State of Wisconsin, have invented certain new and useful Improvements in Machine-Brakes; and I do hereby declare the following to be a full, clear, and exact description of the invention, such as will enable others skilled in the art to which it appertains to make and use the same.

The invention relates to machine brakes, and has for its object to provide a band or strap brake with means for operating the same to apply the brake against the turning moment, in either direction, of the band wheel or shaft, and to automatically reverse the pull on the band when the direction of the force tending to turn the wheel or shaft reverses.

In the accompanying drawings, Figure 1 is a side elevation of a band or strap brake, involving the invention, applied to the shipper shaft of a steam shovel or excavator; Fig. 2 is an enlarged cross section of the shaft end of the brake mechanism, showing the relation of the parts when the brake is applied to the wheel and the latter tends to turn away from the brake shaft; Fig. 3 is a similar view, showing the relation of the parts when the force applied to the shaft of the band wheel tends to reverse the same; Figs. 4 and 5 are a side and plan view, respectively, of one end of the brake operating shaft; Fig. 6 is an end view thereof; Fig. 7 is a cross section on lines *a—a* of Fig. 5; Fig. 8 is a cross section on line *b—b* of Fig. 5; Fig. 9 is a cross section on line *c—c* of Fig. 5;

As hereinbefore referred to, the invention relates to band brakes, and essentially to differential band brakes in which the braking power is adapted to be applied for either direction of rotation of the wheel or shaft to be braked. The band brakes in common use may be divided into two general classes, plain and differential. In the plain band brakes, the heavy pulling or anchor end is fastened to a fixed support, entirely independent of the operating lever, while the other end, after passing around the brake wheel, is attached to the operating lever. In the differential band brake, one end, which is called the light pulling end, is attached to the brake lever at a greater distance or radius

from the axis of revolution of the operating lever than the other or heavy pulling end.

As is well understood, when the handle of the operating lever is moved in the direction to set the brake, the tendency of the lever is to pull the light end of the brake band and to loosen the heavy pulling end thereof, but as the heavy pulling end is at a smaller radius from the axis of revolution than the light pulling end, the net result is to tighten the brake band upon the brake wheel. A brake band of this type pulls much harder on one end than it does on the other, due to the accumulative effect of the friction between the rim of the brake wheel and the brake band, beginning at a point where the light pulling end engages the brake wheel, or, in other words, where the wheel is passing out of contact with the band.

The frictional force caused by the pressure of the band against the wheel, is added to the pull on the light end, and makes a heavier pull on the brake band just back of the point where the band begins to engage the wheel. Following back along the brake band toward the other end, the frictional force is constantly accumulating and increasing the tension in the band, so that when the other end is reached (the heavy pulling end), if the arc of contact is nearly the full circumference, the pull at that end of the band will be two and one-half or three times as great as it is on the light pulling end.

It will be apparent that with the differential arrangement of the operating lever, this heavy pull acts to assist the operator in applying the brake, as it helps to throw the operating lever in the direction which the operator is trying to move it. On the other hand, the light pulling end is opposing the action of the operator. As the pull on the heavy end is from two to three times as great as the pull on the light end, it is necessary that the leverage on the heavy end should be much shorter, in order that the operator may be obliged to supply a small amount of the required force himself. Obviously, if the leverage of the heavy pulling end is made too great, the brake becomes self-locking, and can only be disengaged by pulling the opposite direction. It will be evident, therefore, that the ordinary type of differential brake can be effectively used in one direction of rotation only, because if the brake wheel is re-

versed, the heavy pull comes on the long leverage and opposes the action of the operator to apply the brake, while the light pull comes on the short leverage. This objectionable operation of the usual style of differential band brake, is quite apparent when the brake is employed in connection with the shipper shafts of steam shovels, or dipper dredges, and the like. In such machines, the brakes have two separate functions; first, when the dipper is suspended in the air and is being lowered toward the bottom, the brake wheels have to hold the weight of the dipper and lower it under control of the operator; second, when the dredge is digging along the bottom, the brake wheels are required to hold the dipper into the cut, and prevent the hoisting rope pulling the dipper away from the bottom during the digging movement, it is therefore necessary, in order to make a differential band brake double acting, to provide some means for reversing the relation of the fulcrum to the two ends of the band simultaneously with the reversal of the direction of motion in the wheel to be braked. This may be conveniently accomplished by the arrangement of the brake operating shaft and the appurtenant part shown in the drawings, in which *a* indicates the shaft which is to be braked, and which, in the present instance, is shown as the shipper shaft of a dipper dredge, although, of course, it will be understood that the invention applies to any type of shaft which it is desired to brake in either direction. On the shaft, *a* is the brake wheel *b*, surrounding which is the brake band or strap *c* faced with the usual wearing blocks *d*. The ends of the brake band are connected to the operating shaft *e*, at points on either side of the center thereof, by any suitable means, so that when the shaft is rotated by the operator to apply the brake, the end of the upper reach of the band moves downward and the end of the lower reach moves upward, thereby causing the band to tightly embrace the periphery of the wheel *b*.

Instead of providing the shaft *e* with the usual circular bearing of the ordinary type, said shaft is mounted in a bearing which loosely embraces or incloses the shaft, so as to permit the latter to have a limited movement in the bearing in a direction transverse to the axis of the shaft. In the type of brake shown, it will be understood that there are two brake wheels, and, therefore, two bearings, but it will be apparent that a single brake wheel and band and a single bearing would in other cases be quite effective. Each bearing consists of a bottom member *n*, provided with a section *s'* which is generally eccentric to the shaft and is provided with an upwardly facing lug *t*. The upper member of the bearing is formed as a cap portion *o*, fitting the lower member and secured thereto

by the usual strap *p*, and having an inner surface likewise eccentric to the shaft, but disposed oppositely to the eccentric portion *s'* in the lower bearing to constitute a recess *t'* between the shaft and the inner surface of said portion *o*. Said upper member *o* also has a lug *s* which faces downwardly and is, therefore, oppositely disposed with respect to the lug *t* on the lower member *n*. The shaft *e*, where the same passes through the bearing, is provided with two oppositely disposed lugs *i* and *j*, which are adapted to cooperate with the corresponding lugs *s* and *t* on the bearing, under conditions to be herein-after more particularly referred to. These lugs are formed as the terminations of generally eccentric cam shaped portions *i'* and *j'*, respectively, on the shaft. On the side of the bearing adjacent to the co-operating lugs *i* and *s*, the cap member *o* is secured by a heavy through-bolt *r*, which passes through the flange on said cap member and the member *n* to the foundation, in order to resist the heavy strains imposed upon the cap member under certain conditions of operation. The outer end of the shaft, beyond the lug portions *i* and *j*, is provided with a flange *h*, upon the periphery of which the operating lever *h'* is secured by a suitable key. Beyond the flange *h*, toward the end, the shaft is provided with means for securing the respective ends of the brake strap *c*, which means may conveniently consist of a single recess *g* shaped to receive a cross pin in the end of a tension bolt *m* secured to the lower reach of the band *c*, and the other side of the shaft is provided with two recesses *f*, *f*, which receive the bifurcated or double strap member *c''* attached to the upper reach of the band *c*, and secure the same to the shaft by means of a through-pin.

The operation of the apparatus, as herein-before described, is substantially as follows: Assuming that the force acting upon the shaft *a* tends to revolve it in the direction of the arrow shown in Fig. 1, and the operator has applied the brake to counteract this force by moving the lever *h'* to the left, the lower member of the strap or band *c* then becomes the tight side of the brake, while the upper member receives only the pull of the operator; and the lower member is, therefore, the heavy pulling end of the brake, while the upper member is the light pulling end. Under these conditions, the wheel *b* and shaft *a* may be held absolutely stationary, or allowed to rotate at the desired speed under perfect control, and the shaft *e* occupies the relation to its bearing shown in Fig. 3, to wit, the lug *j* has been moved down into engagement with the lug *t* on the lower member of the bearing, and the heavy pulling end of the band acting with lug *t* as a fulcrum, assists the operator to swing the shaft downward until the lug *i* occupies a position consider-

ably below lug *s*. Should the turning moment or force tending to rotate the shaft *a* and brake wheel *b* be suddenly reversed, the relation of the shaft to its bearing will be instantly changed to that shown in Fig. 2, and the direction of the pull of the band will be automatically reversed. As the wheel *b* tends to move backward, the pull on the upper member of the band *c* immediately draws the lug *i* on the shaft into engagement with lug *s* on the upper member *o* of the bearing, simultaneously disengaging lugs *j* and *t*, and maintaining the braking force between the band and the periphery of the wheel *b* throughout the engagement of said parts without further action on the part of the operator. Should the shaft *a* again be subjected to a reversal, the brake shaft *e* will shift to its original position as shown in Fig. 3, and maintain the full braking force on the wheel without requiring the necessity of further manipulation by the operator. When it is desired to completely release the brake, it will be understood that the lever *h* will be released, and the brake shaft *e* will move to an intermediate position, permitting the band *c* to lie loosely about the wheel *b*.

Although the foregoing description is directed more particularly to machine brakes of the differential type, *i. e.*—brakes in which the respective ends of the strap or band are attached to the brake-lever or operating shaft in such a manner that the heavy pulling end assists the operator to apply the brake,—it is to be understood that the invention is not limited to such differential brakes, but may also be employed in the brakes which are not differential. In the construction described such a case would occur if the co-operating lugs, which act as fulcrums, on the brake-shaft and its inclosing bearings, were placed in line with the points of attachment of the ends of the brake-band to the brake-shaft. It will thus be seen that the essence of the herein described invention lies in a brake with shifting fulcrums which may, or may not be so arranged as to give differential action.

Having thus described my invention, what I claim and desire to secure by Letters Patent, is:—

1. A band brake comprising a brake wheel, brake band, a brake lever which is used to tighten the brake band upon the brake wheel, and means for automatically shifting the fulcrum of the brake lever when the direction of rotation of the brake wheel is reversed, whereby the heavy pulling end and

the light pulling end shall have the same relation to the fulcrum and to each other in either direction of rotation.

2. A differential band brake comprising a brake wheel, brake band, a brake lever which is used to tighten the brake band upon the brake wheel, and means for automatically shifting the fulcrum of the brake lever when the direction of rotation of the brake wheel is reversed, whereby the heavy pulling end and the light pulling end shall have the same relation to the fulcrum and to each other in either direction of rotation.

3. A differential band brake, comprising a brake band, a shaft to which the ends of the band are connected to apply the brake, and a bearing in which said shaft is mounted to permit transverse movement of the shaft, the shaft and bearing having co-operating means for automatically shifting the fulcrum of the shaft when the direction of rotation of the brake wheel is reversed, whereby the heavy pulling end and the light pulling end shall have the same relation to the fulcrum and to each other in either direction of rotation.

4. A differential band brake, comprising a brake band, a shaft to which the ends of the band are connected to apply the brake, and a bearing in which said shaft is mounted to permit transverse movement of the shaft, the shaft having oppositely disposed lugs and the bearing having co-operating lugs constituting alternate points of engagement or fulcrum, whereby the heavy pulling end and the light pulling end shall have the same relation to the fulcrum and to each other in either direction of rotation.

5. A differential band brake, comprising a brake band, a shaft to which the ends of the band are connected to apply the brake in either direction, and a bearing in which the shaft is mounted to permit a limited transverse movement of said shaft, the shaft having oppositely disposed eccentric lugs and the bearing having co-operating shoulders adapted to be alternately engaged by the corresponding lugs on the shaft to automatically shift the fulcrum around which said shaft rotates when the direction of rotation of the band wheel is reversed.

In testimony whereof I affix my signature, in presence of two witnesses.

WALTER FERRIS.
